UNITED STATES PATENT OFFICE

PAUL F. PAIGE, OF DETROIT, MICHIGAN, ASSIGNOR TO FORBES LITHOGRAPH MANUFACTURING COMPANY, OF BOSTON, MASSACHUSETTS, A CORPORATION OF MASSACHUSETTS

CONTAINER WITH ATTACHED CIRCULAR

Application filed June 19, 1926. Serial No. 117,044.

This invention relates to containers and especially to cartons or cans in which commodities are packaged for sale and the object is to provide in connection with such 5 a container a writing, usually in the nature of a circular or advertisement addressed to the purchaser, attached exteriorly to the container in such a manner as to remain in position while the container is handled in 10 the course of trade, yet being readily accessible to the purchaser. Thus, for instance, the writing may be a folder containing instructions or suggestions as to the use of the commodity packaged in the container.

15 My invention will be readily understood from the following description of an illustrative embodiment thereof taken in connection with the accompanying drawings, wherein I have shown a writing attached to a cylindrical container in the nature of a can, the combination constituting a specific embodiment of my invention. In these drawings—

Fig. 1 is an end elevation of the folder 25 separated from the container and shown partly unfolded for clearness;

Fig. 2 is a perspective on a somewhat smaller scale of the container with the folder secured thereto; and

30 Fig. 3 is a plan view showing the folder opened, as by a purchaser, and with part broken away.

In the example of my invention herein shown the writing which is attached to the can 5 is shown as a folder formed from a single piece of paper. Such folder may embody a front 7 and a back 9 connected along a hinge line 11 at the left. The front 7 may have a marginal extension, herein shown as a flap 13 connected to one edge only of said front, that opposite the hinge line 11, and adapted to be folded downwardly and under and which may, as herein shown, overlap the edge of the back 9. The rearwardly facing surfaces of the back 9 and of the flap 13 are adhesively secured to the outer wall of the container, being shown in Fig. 2 as secured to one of the circular ends or bases of the cylindrical can. When the 50 customer receives the package in the form

shown in Fig. 2, he may open the folder by severing the flap 13 from the edge of the front 7 and, if desired, as indicated in that figure, directions so to do may be printed along the margin of the front 7. The front 55 7 may then be lifted like the cover of a book and thrown over toward the left in the manner indicated in Fig. 3, exposing the clean fresh printing at the interior.

To provide for a greater amount of printed matter than could be printed on the small folio 7—9 additional pages may be housed between the front and back. I have herein shown an extension 15 from the free edge of the back 9, which may be folded over in between the front and back and herein this extension is shown long enough to make two leaves, that is, four pages, and, as shown in Fig. 1, it may be folded over in zigzag to lie under the front 7. Such interior leaves formed by an extension of the back 9 may, if it is desired to preserve them, be readily separated from the back which remains attached to the container.

It will be seen from the preceding description that the pages of the circular or folder are confined closely to the container in such a manner that it is not likely to be damaged or pulled off in the handling which the container receives in shipment and merchandising. In the form illustrated the front 7 is substantially smooth and unbroken and not likely to be caught and torn and it affords a surface well adapted to receive display printing or an attractive design. At the same time the folder is readily accessible to the customer to be opened and perused when desired. In the case of a can such as is illustrated in Fig. 2 having a marginal bead 17 the circular may be placed within the circumference of the bead and will be protected thereby and in such instance may form a booklet of considerable thickness.

It will be understood that the printed matter may comprise letter-press of any desired tenor or ornamental or instructive pictures as may be consistent with the purposes for which it is attached to the container.

Having described in detail the particular 100

embodiment of my invention illustrated as an example thereof in the accompanying drawings without intending thereby to limit the scope of my invention to the form shown and specifically described, I will express in the following claims what I consider new and desire to secure by Letters Patent.

Claims:

1. In combination with a container a booklet-like folder having a back and a front, said front having a marginal portion folded over rearwardly, the back and said portion being secured to the container and said front and back presenting disconnected top and bottom edges providing for insertion of a tool for severance of said portion from the said front, such severance permitting the front to be raised for inspection of the interior of the folder.
2. In combination with a container a booklet-like folder having a back and a front, said front having a marginal portion folded over rearwardly, the back and said portion being secured to the container and said front and back presenting disconnected top and bottom edges providing for insertion of a tool for severance of said portion from the said front, such severance permitting the front to be raised for inspection of the interior of the folder, said folder having additional pages carried between the front and back.
3. In combination with a container a booklet-like folder having a back and a front, said front having a marginal portion folded over rearwardly, the back and said portion being secured to the container and said front and back presenting disconnected top and bottom edges providing for insertion of a tool for severance of said portion from the said front, such severance permitting the front to be raised for inspection of the interior of the folder, said back having an extension providing additional pages folded between said front and back.
4. In combination with a container a booklet-like folder having a back and a front, said front having a marginal portion folded over rearwardly, the back and said portion being secured to the container and said front and back presenting disconnected top and bottom edges providing for insertion of a tool for severance of said portion from the said front, such severance permitting the front to be raised for inspection of the interior of the folder, said back having an extension folded in zigzag to provide a plurality of leaves housed between said front and back.
5. In combination with a container a folder formed from a strip of paper and having a back portion adhesively secured to said container, a projecting part folded to overlie said back, a front and a cooperating flap adhesively securing said front over said

folded projecting part to retain the same against the back, severance of said flap permitting the front to be raised for inspection of the folded projecting part.

In testimony whereof, I have signed my name to this specification.
